UNITED STATES PATENT OFFICE.

GARDINER W. CHIPLEY, OF CHICAGO, ILLINOIS, ASSIGNOR OF ONE-HALF
TO CHARLES W. ARMBRUST, OF CHICAGO, ILLINOIS.

RAILWAY BRAKE-BEAM.

SPECIFICATION forming part of Letters Patent No. 690,099, dated December 31, 1901.

Application filed August 15, 1900. Serial No. 26,933. (No model.)

To all whom it may concern:

Be it known that I, GARDINER W. CHIPLEY, a citizen of the United States of America, and a resident of Chicago, Cook county, Illinois, have invented a certain new and useful Improvement in Railway Brake-Beams, of which the following is a specification.

My invention relates to a certain improvement in brake-beam construction which is 10 designed to permit an initial and continued application of the brake-shoe uniformly for the whole plane of its wearing-face upon the tread of the wheel and also to avoid all torsional strain upon the brake-beam and all 15 unnatural strain upon the brake-rigging.

Heretofore it has been ascertained in practice that the upper portion of the brake-shoe in its initial and continued application is first brought to bear against the tread of the 20 wheel, thus causing the brake-shoe to wear unequally, the upper portion wearing much faster than the lower portion and also imposing a torsional strain upon the brake-beam and unnatural strains upon the brake-rigging. 25 To overcome this unequal wear, avoid such strains, and obtain a uniform application of the brake-shoe to the tread of the wheel, resort has been had to many devices of differing character, in all cases constructed to act 30 either directly upon the brake-shoe or upon the brake-head.

My invention is of such character that the brake-shoe may be secured upon the brake-head and the brake-head upon the brake-beam in the usual manner, the uniform application of the whole wearing-face of the shoe upon the wheel-tread being obtained and the torsional strain of the brake-beam and unnatural strains upon the brake-rigging over- 35 come by novel means, permitting a movement of the brake-beam relative to and independent of the pivotal attachment of the brake-lever to the brake-beam.

Reference may now be had to the accompanying drawings for a particular description of the different means employed for embodying my invention, in which—

Figure 1 is a central longitudinal section through a car-truck. Fig. 2 is a like view, 40 enlarged, of a portion of a car-wheel, showing the initial application of the brake-shoe

to the tread of the wheel. Fig. 3 is a similar view showing the whole face of the shoe uniformly applied to the wheel. Fig. 4 is a perspective view of one form of brake-beam and 55 brake-shoes attached, showing my invention applied. Fig. 5 is a fragmentary perspective view illustrating the movement of the brake-beam independent of the attaching member of the brake-lever. Fig. 6 is a detailed perspective view of the brake-beam strut. Fig. 7 is a detailed view of the attaching member of the brake-lever. Fig. 8 is a detailed perspective view of a modified form of strut. Fig. 9 is a detailed fragmentary perspective 60 view of a modified form of strut and support. Fig. 10 is a perspective view of another type of brake-beam, illustrating the manner of applying my invention. Fig. 11 is a cross-section on the line *a a* of Fig. 10. Fig. 12 is also 65 a perspective view of still another type of brake-beam, showing my invention applied thereto. Fig. 13 is a cross-section on the line *b b* of Fig. 12.

It is found extremely difficult in practice 70 to adjust or so position the brake-beam and the brake-shoes in relation to the car-wheels that the whole wearing-surfaces of the shoe shall be applied initially and continuously and uniformly equally and at all points upon 75 the tread of the wheel. If, in the first instance, the brake-beam and brake-shoes are properly positioned relative to the car-wheels, the wear of the attaching devices displaces such adjustment, which causes the brake- 80 beam to assume a position nearer the track. When the brake-beam and brake-shoes are thus imperfectly adjusted relative to the car-wheels or assume an improper position in relation to the car-wheels, the upper portion of 85 the brake-shoe is first brought to bear against the tread of the car-wheel, leaving the lower end of the shoe standing away from the tread, which lower end or portion of the shoe is un- 90 worn until sufficient material has been worn away from the upper portion of the shoe to allow the whole surface of the shoe to come in contact with the wheel or the face of the upper portion of the shoe is pressed with greater force upon the tread of the wheel 95 than the lower portion, the upper portion thus wearing out much more rapidly than the

lower portion. This unequal application of the shoe to the tread of the car-wheel also imposes a torsional strain upon the brake-beam and a strain upon the brake-rigging.

5 To overcome this unequal wear of the brake-shoe and injurious strain upon the brake-beam and the brake-rigging, I have devised means whereby to permit a movement of the brake-beam relative to and independent of the brake-lever fulcrum, which is accomplished by providing a support for the brake-lever fulcrum so loosely mounted upon or secured to the brake-beam as to permit the brake-beam to have such a movement. The 15 brake-lever when the brakes are applied has a pivotal movement about its fulcrum, and its fulcrum also moves with the brake-beam in a direction toward the car-wheels. In ordinary construction the brake-beam and its 20 fulcrum have these movements only in the application of the brake-shoe to the wheel. By my improved means, hereinafter to be particularly described, the brake-lever is not only permitted to move about its fulcrum and also 25 toward the car-wheels as the brakes are applied in the usual manner, but the attachment for the brake-lever fulcrum being loosely mounted upon the brake-beam permits the latter to rock or turn, and thus bring 30 the entire wearing-face of the brake-shoes upon the tread of the car-wheels, this movement of the brake-beam being independent of but relative to the brake-lever fulcrum and attaching member.

35 In the drawings, having reference first to Figs. 4, 5, 6, and 7, it will be observed that the compression member A of the brake-beam is connected to the tension member B by means of a strut D. The attaching member E for the brake-lever, Fig. 7, comprises in its construction a sleeve E², loosely mounted upon the compression member A of the brake-beam. The arm E³ of said attaching member is slotted at E⁴, and the brake-lever 40 45 G passing therethrough is fulcrumed at G² at said arm. The brake-heads H are secured upon the brake-beam in the ordinary manner, and the brake-shoes J, Figs. 1, 2, and 3, are mounted upon or secured to the brake-heads 50 H, also in the usual way. In the forms shown in Figs. 4, 5, and 6 the brake-beam strut D has a cap D², against which the free end of the arm E³ bears, thus maintaining the beam normally in a horizontal position, and a stay member 55 D³. This construction, it is evident, provides an attaching member for the brake-lever fulcrum, which is loosely mounted at one end upon the brake-beam and free at its other end.

60 Fig. 2 of the drawings illustrates in an exaggerated manner the initial application of the brake-shoe to the brake-tread of the wheel. As illustrated, the upper portion of the brake-shoe is first brought into contact 65 with the tread of the wheel. Under ordinary conditions the brake-shoe is pressed unequally at its upper portion upon the tread of

the wheel initially and during its continued application; but with the construction described it is apparent that the brake-shoe is brought to bear and pressed uniformly upon the wheel-tread, as shown in Figs. 1 and 3, by reason of the fact that the brake-beam is permitted a rocking or tilting movement unrestrained by the support for the brake-lever. 75 When the brakes are set, the brake-beam has a forward movement carrying the brake-lever fulcrum toward the wheels, said brake-lever having a pivotal movement upon its fulcrum; but when the upper portion of the brake-shoe 80 is brought to bear unequally upon the tread of the wheel an equal self-adjustment is effected as the tension member B of the brake-beam moves upwardly in the direction of the arrow, Fig. 3, the compression member A 85 rocking and the brake-lever-fulcrum attaching member remaining in a relatively stationary position, thus bringing the shoe to bear equally at all points upon the tread of the wheel. It is apparent that the brake-shoes 90 self-adjust themselves upon the wheel-tread because of this unrestricted tilting or rocking movement of the brake-beam independent of but relative to the brake-lever fulcrum, which latter, so far as this movement of the brake-beam is concerned, remains relatively stationary. 95

Upon the application of the brake-shoes to the wheel-tread the rotation of the wheels tends to exert an upward or downward pull 100 upon the brake-shoes, depending upon the direction of rotation of the car-wheel. Under these conditions the brake-beam is either raised or lowered. As the attaching devices of the brake-beam become worn the horizontal position of the beam and its relation to the wheels become displaced, which in the ordinary construction causes unequal application of the brake-shoes. With this construction which I have described it is evident 105 that the brake-beam may be positioned at such a distance from the track as to permit a tilting or rocking of the brake-beam, which will equally and uniformly apply the shoes notwithstanding the direction of rotation of 110 the car-wheel. 115

It may be found in practice that the lower portion of the brake-shoe in some cases wears more rapidly than the upper portion, and to provide for such cases the form of construction shown in Fig. 8 may be adopted, in which the attaching member E³ at its free end is not engaged by the strut D, thus permitting a tilting or rocking movement of the brake-beam in either direction. In this form of 125 construction it is apparent that the brake-beam is permitted such a movement as to equally apply the shoe to the wheel-tread whether the wear occurs at the upper portion or at the lower portion. 130

In Fig. 9 I have shown a modified form of strut D, forming a loop projected from the compression member A of the brake-beam and so arranged that the brake-beam is main-

tained in a normally horizontal position by the engagement of the free end of the brake-lever support-arm E³ against the loop of the strut. In this construction I have shown a 5 sleeve J² for the reception of the tension member B, and in the form shown in Fig. 8 a recess J³ is provided for the reception of the said tension member.

In Fig. 10 I have shown my invention applied to another form or type of brake-beam commonly in use. To accomplish this application, I provide a strut K of such a form as to embrace the brake-beam K² and inclose it. This brake-beam comprised in construction 15 a flange K³, a web K⁴, and an annular elongated head K⁵. The strut K is so formed as to receive the head K⁵ of the brake-beam and permit it to rotate or rock upon said strut. The brake-lever support-arm L is secured to 20 and extended from the strut K. From this description it is clear that the brake-beam K² is permitted a movement independent of, but relative to, the brake-lever fulcrum-support, as the brake-beam may rock or tilt without 25 in the strut, as shown more clearly in Fig. 11. The brake-lever attaching member is, as stated, loosely mounted upon the brake-beam, the connection preferably being of a pivotal or hinge-like nature, so as to permit the beam 30 to turn or rotate freely in the bearing provided by the end of said member. In applying the shoes this brake-lever attaching member exerts a pull upon the beam—that is to say, it sustains a tensile strain—and in this 35 way the brake-lever is operative through the medium of this attaching member to draw the brake-shoes into contact with the wheels.

Fig. 12 illustrates my invention as applied to still another form of brake-beam, which 40 consists of an elongated annular head M and web M², which is semicircular in form. In this construction the brake-lever-support arm M³ has a loop M⁴ at its free end to receive the brake-lever and is pivotally secured upon the 45 head M of the brake-beam. By this form of construction the brake-beam may move independently of and in relation to the brake-lever support to adjust the shoe upon the wheel-tread.

50 The brake-beam is maintained in a horizontal position in the form shown in Fig. 10 by means of the strut K, and in the form shown in Fig. 12 the web M² of the brake-beam rests upon the support-arm M³ of the brake-lever.

55 Having thus described my invention, what I claim as new, and desire to secure by Letters Patent, is—

1. In a brake-beam construction, a brake-beam, brake-shoes carried by and rigid with 60 said beam, a brake-lever adapted, and arranged for applying said shoes, and a connection between said lever and beam adapted to permit the beam to turn or rock relatively to the lever and about a longitudinal axis, substantially as described.

2. In a brake-beam construction, a brake-beam, brake-shoes carried by and rigid with

said beam, a brake-lever adapted and arranged for applying said shoes, and a connecting member between said lever and said beam, 70 said connecting member having a pivotal or hinge-like connection with the beam, whereby the latter is free to turn or rock about a longitudinal axis, substantially as described.

3. In a brake-beam construction, a brake-beam, brake-shoes carried by and rigid with 75 said beam, a brake-lever, a connecting member adapted and arranged for connecting said lever with said beam, said connecting member being arranged to exert a pull upon the beam in a direction to apply the said shoes, and said connecting member having a swinging or hinge-like connection with said beam, whereby the beam can turn or rock about a longitudinal axis, substantially as described. 85

4. In a brake-beam construction, a brake-beam, brake-shoes carried by and rigid with said beam, and adjusting devices adapted and arranged for exerting a pull upon the beam, so as to apply the said brake-shoes, 90 said adjusting devices being so connected with the beam as to permit the latter to turn or rock about a longitudinal axis, substantially as described.

5. In a brake-beam construction, the combination of a brake-beam, brake-shoes carried by and rigid with said beam, a brake-lever, a connecting member for connecting said lever with said beam, said connecting member extending in the same direction as the brake-shoes and having an end portion formed with a bearing for the brake-beam, whereby the latter is free to turn or rock about a longitudinally-extending axis, substantially as described. 95

6. In a brake-beam construction, the combination of a suitable brake-beam, brake-shoes carried by and rigid with said beam, a brake-lever, a connecting member for connecting said lever with said beam, said connecting member extending from the beam in the same direction as the brake-shoes, and a strengthening device applied to said beam, said strengthening device resting upon the said connecting member when the brake-shoes are not applied, and a pivotal or hinge-like connection between said connecting member and said brake-beam, whereby the latter is free to turn in a direction to lift the said strengthening device from the connecting member when the brake-shoes are applied, substantially as described. 105

7. In a brake-beam construction, the combination of a brake-beam, brake-shoes carried by and rigid with said brake-beam, a connecting member having one end provided with a bearing adapted to engage a cylindric portion of said beam, a brake-lever having a suitable connection with the other end of said connecting member, the pivotal or hinge-like 125 connection thus provided between the lever and brake-beam permitting the latter to turn or rock relatively to the lever about a longitudinal axis, substantially as described. 130

8. In a brake-beam construction, the combination of a brake-beam, brake-shoes carried by and rigid with said beam, a brake-lever, and a connecting member for connecting said lever with said beam, the lever and said connecting member being adapted and arranged to exert a pull upon said beam in a direction to apply said shoes, and said connecting member having a pivotal or hinge-like connection with the beam, whereby the latter is free to turn or rock relatively to the brake-lever and about a longitudinal axis, substantially as described.

9. In a brake-beam construction, the combination of a brake-beam, brake-shoes carried by and rigid with said beam, a strengthening device applied to said beam and constructed with a suitable strut, a brake-lever, a connecting member for connecting said lever with said beam, said connecting member being provided with a bearing in which the said beam is free to turn or rock about a longitudinal axis, and said strut being adapted and arranged to rest upon the connecting member when the brake-shoes are free or not applied, and the beam turning or rotating when the shoes are applied to an extent to lift or raise the strut from the connecting member, substantially as described.

10. In a brake-beam construction, a brake-beam, brake-shoes mounted thereon or secured thereto, a strut for said brake-lever and a brake-lever attaching member loosely mounted at one end upon the brake-beam and free at its other end, whereby said brake-beam is permitted a movement independent of and relative to the brake-lever.

11. In a brake-beam construction, the combination of a brake-beam with brake-shoes rigidly secured to the ends thereof, a strut located near the center of the beam and at the same side at which the brake-shoes are located, a tension member connecting the ends of the brake-beam and engaging the end

of said strut, a brake-lever attaching member rotatively mounted upon said brake-beam and arranged to swing in an opening formed in said strut, and a brake-lever arranged to exert a pull upon said brake-lever attaching member for the purpose of applying the brake-shoes, the said strut resting normally on the brake-lever attaching member and rising therefrom when the shoes are applied, substantially as described.

12. In a brake-beam construction, the combination of a brake-beam having brake-shoes rigidly mounted or secured at its ends, a strengthening member extending longitudinally of said beam, a brake-lever, a connecting-bar for connecting said brake-lever with said brake-beam, the connection between said bar and brake-beam being of such character as to permit rotation on the part of the brake-beam relatively to the brake-lever, the said strengthening member resting normally upon the said bar for connecting the brake-lever with the brake-beam, and said strengthening member rising from said bar when the shoes are applied as a result of a pull exerted upon said beam by the brake-lever, substantially as described.

13. In a brake-beam construction, a brake-beam consisting of a compression member and a tension member, a strut, and a brake-lever attaching member connected loosely to the compression member.

14. In a brake-beam construction, a brake-beam, shoes mounted thereon or secured thereto, a strut and a brake-lever attaching member loosely connected to the brake-beam and free at the other end and a stop for said free end.

Signed by me at Chicago, Cook county, Illinois, this 13th day of August, 1900.
